UNITED STATES PATENT OFFICE.

JOHN E. CHACE, OF ADAMSDALE, MASSACHUSETTS.

SPOOL CARRIER FOR BRAIDING MACHINES.

Application filed April 20, 1923. Serial No. 633,461.

To all whom it may concern:

Be it known that I, JOHN EDDY CHACE, a citizen of the United States, residing at Adamsdale, in the county of Bristol and 5 State of Massachusetts, have invented new and useful Improvements in a Spool Carrier for Braiding Machines, of which the following is a specification.

This invention relates to certain new and 10 useful improvements in a spool carrier for braiding machines and especially to that type of spool carrier set forth in my application for patent on a spool carrier for braiding machines filed November 19, 1920, 15 Serial No. 432,918.

In the former application the invention was designed to dispose and arrange the entire let-off mechanism below the bobbin whereby all the weight would be so located 20 as to produce a better balanced structure.

The present invention has for its primary object to provide a simplified structure in the let-off mechanism, the latter being arranged, as in the former case, adjacent the base of the carrier.

A further object resides in the association and mounting of the bobbin-holding pawl and its disengaging means whereby the several parts are guided and held 30 against being easily distorted or otherwise rendered inoperative.

The invention further resides in the features of construction and the arrangements and combinations of parts herein- 35 after described and claimed reference being had to the accompanying drawings wherein:

Figure 1, is a side elevation of a bobbin carrier embodying the present invention; 40 Figure 2, is a similar view taken at right angles to the plane of Figure 1;

Figure 3, is a view similar to Figure 1, but depicting certain parts in vertical section and the bobbin ratchet free from the 45 pawl;

Figure 4, is an elevation of Figure 3 viewing the same from the pawl side;

Figure 5, is a horizontal sectional view of line 5—5 of Figure 1; and

50 Figure 6, is a similar cross section on line 6—6 of Figure 1.

Referring more in detail to the drawings, the carrier comprises a base 1 from which depends a stub shaft 2 to which 55 power is applied in a manner well known

to the braiding machine art. Rising from the base 1 is a standard 3 which supports a bobbin support 4 thereabove and also a bobbin spindle 5 on which is rotatably mounted the bobbin 6, said bobbin carrying 60 at its base or lower end a ratchet 7 which has rotatable bearing on the support 4. A guide arm 8 also extends upwardly from the base 1 along side the bobbin and is connected intermediate its ends to the laterally extending bobbin support 4, thereby adding rigidity to the structure. The arm has that portion between the base 1 and support 4 vertically slotted to constitute a vertical guide 9 for the arm 10 of a bell 70 crank lever which is pivoted at 11 between a pair of ears 12 extending from the opposite side of standard 3, the latter being also slotted, as at 13, to receive the arm 10. The bell crank lever has a short arm 14 75 extending upwardly, and on the upper end thereof is secured a guide 15 which is designed to guidingly embrace or straddle the standard, as is most clearly depicted in the drawings. A pawl 16 is also mounted on pivot 11 for engaging in the teeth of ratchet 7, being urged to its operative position by the spring pressed plunger 17 which is slidably housed or guided in the lower end portion of the standard for exerting outward pressure on the depending 80 extension 18 of the pawl. The lateral bobbin support 4 has its adjacent end formed with a cut-out 19 to guidingly receive the upper end of the pawl 16. Obviously, upward 85 movement of arm 10 will rock arm 14 into engagement with the pawl 16, and carry the same out of engagement with the ratchet 7 so that the bobbin will be free to rotate. Downward movement of arm 10 will permit the resilient device 17 to 90 return the pawl 16 to its operative position.

The guide arm 8, above the support 4, is provided with a thread eye 20, and at its 100 upper terminal with a delivery eye 21. Adjacent the eye 20, and on the inner side of the arm is a guide hook 22. The tension slide 23 is guided vertically on the arm 8 and carries on its inner side a thread hook 105 24, and on its outer side a similar hook 25, the shaft or wire of which extends downwardly at 26 and is pivotally connected to the arm 10. The bobbin thread 27 in leaving the bobbin is directed over hook 110

22, under hook 24, through the guide opening or eye 20 and under hook 25 from whence it goes to the delivery eye 21.

In operation, with the bobbin held 5 against rotation by the pawl 16, the thread 27 will be gradually tightened and thereby lift the tension slide vertically. Such movement will also lift the arm 10 which will in turn cause the arm 14 to impinge 10 against the pawl 16 and act as a knock-off to effect disengagement of the pawl from the ratchet 7. The bobbin, being thus released, will feed out its thread by reason of the tensioning slide gravitating, with the indirect aid of the cushioning element or device 17. When a definite length of thread has been unwound from the bobbin the latter is again arrested by the pawl 16.

The tension responsive slide is depicted 20 as being formed from a pair of cross wires, the wire 25—26 constituting the vertical strand while the horizontal strand is looped about the guide arm 8 with both ends being arranged toward the inner side thereof and 25 with one end extended upwardly to form the hook 24. The slide, therefore, would present a cruciform in plan and may be constructed from an integral piece of metal or by separate strands or sections soldered together as herein depicted.

The pawl 16 is preferably constructed 30 from a single strip of metal bent upon itself substantially one-third of its length so that the extension 18 will be of double thickness. 35 This construction also permits of the pawl having a double bearing on the pivot 11 as shown clearly in Figures 4 and 6. The upper end is twisted at right angles and consists of a single thickness for engaging 40 the ratchet.

The foregoing construction is of a very simplified nature which is especially desirable in a bobbin carrier wherein all the let-off mechanism is arranged beneath the bobbin. The bobbin is readily removable without deranging the mechanism and the latter is also readily accessible for repair or adjustment.

Having thus described my invention, 50 what I claim as new and desire to secure by Letters Patent is:—

1. A bobbin carrier comprising a base, a superposed bobbin support, a standard spacing the latter from the former, a spindle upstanding from the support, a bobbin-connected ratchet rotatable on the spindle, and a guide arm extending upwardly from the base alongside the spindle and connected to the bobbin support, the arm being provided 55 with a vertical guide slot intermediate the support and the base and having vertically spaced thread openings above the support, tensioning means slidably mounted on the arm for engaging the bobbin thread passing through the thread openings, a pawl piv-

oted to the standard and engaging the ratchet, and a bell-crank lever pivoted to the standard and having one arm operable in the guide slot of the guide arm and connected to the tensioning means, the other arm of said bell crank lever having a forked part to guidingly straddle the standard and adapted to effect disengagement of the pawl from the ratchet. 70

2. A bobbin carrier comprising a base, a superposed bobbin support, a standard spacing the latter from the former, a spindle upstanding from the support, a bobbin-connected ratchet rotatable on the spindle, an arm extending upwardly from the base alongside the spindle and connected to the bobbin support, the arm being provided with a vertical guide slot intermediate the support and the base and having vertically spaced thread-openings above the support, tensioning means slidably mounted on the arm for engaging the bobbin thread passing through the thread openings, a pawl pivoted to the standard for engaging the ratchet and having a depending extension, 80 spring means engaging the extension for urging the pawl to its operative position, and means guided in the slot of the arm and connected to the tensioning means for being operated by the latter to disengage the 85 pawl from the ratchet. 90

3. A bobbin carrier comprising a base, a superposed bobbin support, a standard spacing the latter from the former, a spindle upstanding from the support, a bobbin-connected ratchet rotatable on the spindle, an arm extending upwardly from the base alongside the spindle and connected to the bobbin support, the arm being provided with a vertical guide slot intermediate the support and the base and having vertically spaced thread-openings above the support, tensioning means slidably mounted on the arm for engaging the bobbin thread passing through the thread-openings, a pawl pivoted to the standard for engaging the ratchet, 100 said bobbin support having a cut-out part to guidingly receive the pawl, and means guided in the slot of the arm and operable by the tensioning means for disengaging 105 the pawl from the ratchet. 110

4. A bobbin carrier comprising a rotatably supported bobbin holder, a support therefor, means for arresting the holder against movement, a guide arm, a slide mounted on the arm and consisting of a length of wire bent around the arm with one end extended upwardly to form a thread hook and a second length of wire secured to the arm-embracing portion of the first wire and having its upper terminal formed with a thread hook, and means connected to the lower end portion of the second wire for rendering the arresting means inoperative. 120

5. A bobbin carrier comprising a bobbin 125

- support, a bobbin-connected ratchet rotatably mounted thereon said support having spaced guide parts extending beyond the periphery of the ratchet, a pivotally mounted 5 pawl formed from a single strip of metal bent upon itself to provide a double thickness at one end and a single thickness at the opposite end, the latter end being guided by said spaced guide parts of the support and 10 engaging the ratchet, and said double thickness and extending below the pivotal mounting of the pawl, resilient means exerting pressure against the latter end, and means operable according to the tension on the bobbin 15 thread of disengaging the pawl from the ratchet.
6. A bobbin carrier comprising a base, a standard rising therefrom, a bobbin support on the standard, a guide arm rising from the 20 base up along side of the bobbin, thread-tension means guided by the arm, said arm and standard being provided with registering slots, a bell crank lever having one arm guided in the registering slots and connected 25 to the tension means, and bobbin-arresting means adapted to be rendered inoperative by the arm of the lever.
7. In a bobbin carrier, a base, a vertical bobbin support on the base, a bobbin ratchet 30 on the support, a pawl for the ratchet pivoted between its ends to the support, spring means for tensioning the lower end of the pawl, a bell crank lever pivoted to the support and having a vertical arm formed to engage the 35 upper end of the pawl, a guide connected to the said arm and straddling the support, a vertical arm on the base, a thread engaged slide on said last named arm, and a connection between the slide and the other arm of the bell crank lever.
8. In combination with a rotatable bobbin carrying ratchet, and a vertical arm having thread engaging parts, a vertically movable slide on the arm having thread engaging 45 parts whereby to actuate the slide by the thread movements, a pawl for rendering the ratchet inoperative, a pivoted knock-off device for the pawl, and means connecting the knock-off device to the slide for positively 50 rocking the knock-off device about its pivot upon both upward and downward movement of the slide.
9. In combination with a rotatable bobbin carrying ratchet, and a vertical arm having thread engaging parts, a vertically movable slide on the arm having thread 55 engaging parts whereby to actuate the slide by the thread movements, a vertically disposed pawl formed to engage the ratchet, a bell crank lever, having a vertical arm constituting a knock-off device to engage and render the pawl inoperative, and a rod connected to the slide and to the other arm of the bell crank lever to actuate the same.
10. In combination with a rotatable bobbin carrying ratchet, a vertical arm having thread engaging parts, a vertically movable slide on the arm having thread engaging parts whereby to actuate the slide by the thread movements, a vertically disposed 65 pawl pivoted between its ends and having its upper end formed to engage the ratchet, spring means for tensioning the lower end of the pawl, a bell-crank lever having a vertical arm, constituting a knock-off for engaging the inner side of the pawl to render same inoperative, and a rod connected to the slide and to the other arm of the bell crank lever.
11. In a bobbin carrier, a rotatably supported bobbin holder, means for arresting movement of the holder, means to actuate the arresting means, a guide arm and a slide on the arm including a member embracing the arm and having an upwardly extended part to form a thread engaging part, a vertical member connected to the first member and having a thread engaging part on its upper end and having its lower end projecting downwardly below the slide, and means to connect the lower end of the vertical member to the said means for actuating the arresting means.
12. In combination with a rotatable bobbin carrying ratchet having horizontal teeth and a vertical arm having thread engaging parts, a vertically movable slide on the arm having thread engaging parts whereby to actuate the slide by the thread movements, a pivoted vertically disposed pawl having its upper 95 end formed to engage the ratchet teeth for rendering the ratchet inoperative, a knock-off device having a part engaged with the pawl between the pivot and upper end thereof, and means connected to the slide and 100 connected to the knock-off device for actuating the latter.
13. In combination with a vertical support, and a rotatable bobbin carrying ratchet thereon, a vertical arm having thread engaging parts, a vertically movable slide on the arm having thread engaging parts whereby to actuate the slide by the thread 110 movements, a pawl for rendering the ratchet inoperative, a knock-off device for the pawl, guiding means connected to the knock-off device and engaging said vertical support, and means connecting the knock-off device to the slide for positively actuating the 115 knock-off device.
- 120 In testimony whereof I have signed my name to this specification in the presence of two subscribing witnesses.

JOHN E. CHACE.
